(57) **CLAIM**

The ornamental design for a dual lit grab rail assembly, as shown and described.

DESCRIPTION

FIG. 1 is a perspective view of a grab rail assembly according to the present design, including a ribbed surface treatment; FIG. 2 is a right side view of the grab rail assembly of FIG. 1; FIG. 3 is a left side view of the grab rail assembly of FIG. 1; FIG. 4 is a top view of the grab rail assembly of FIG. 1; FIG. 5 is a bottom view of the grab rail assembly of FIG. 1; FIG. 6 is a first end view of the grab rail assembly of FIG. 1; and, FIG. 7 is an opposite end view of the grab rail assembly of FIG. 1.

The broken lines shown in FIGS. 1-7 illustrate portions of the dual lit grab rail assembly which do not form part of the claimed design.

The dual lit rail assembly is shown with a symbolic break lines along its length. The appearance of any portion of the dual lit rail assembly between the break lines forms no part of the claimed design.

1 Claim, 5 Drawing Sheets
